UNITED STATES PATENT OFFICE.

WALTER S. AUSTIN, OF GRAND RAPIDS, MICHIGAN.

CHANGE-SPEED GEARING.

1,091,618.

Specification of Letters Patent. Patented Mar. 31, 1914.

Application filed August 12, 1913. Serial No. 784,347.

To all whom it may concern:

Be it known that I, WALTER S. AUSTIN, a citizen of the United States, residing at Grand Rapids, Michigan, have invented certain new and useful Improvements in Change-Speed Gearing, of which the following is a specification.

This invention relates to change-speed gearing especially adapted to automobiles.

10 In the practical construction of the change-speed gears for automobiles, various problems are encountered. The direct drive of the engine, by which I mean the direct connection by a suitable pinion on the driving shaft to the bevel gear on the axle, is most desirable. The average ratio of this pinion to the gear is in the neighborhood of 1 to $3\frac{1}{2}$, this proportion being intended to meet the average conditions which a car 20 counters. A change-gear speed box is provided in conjunction with the same for emergency use and to provide a reverse gear and a low gear for hill climbing and bad roads, and the direct drive gears of such 25 ratio as to handle the car effectively, both on the road and in heavy traffic. This arrangement does not provide a suitable direct drive for varying conditions. A road may be in perfect condition today, and, owing 30 to weather conditions, become heavy tomorrow, and with but a single proportion of direct drive gear the car will be working at its best under only one condition.

It is, therefore, my purpose to provide in 35 my improved change-speed gear one direct drive of such proportion that it meets all ordinary conditions and of substantially the proportion usually adopted by manufacturers of automobiles at the present time, 40 and to provide a second direct drive gear of such proportion as to take care of the car under favorable road conditions. By this means it will be possible to operate on one direct drive which is of the average proportion 45 for ordinary conditions which I denominate the low speed drive, and on a second direct drive of higher speed where the conditions are more favorable, which I de-

nominate the high speed drive. In practice, this results in economizing fuel, saving 50 of lubricant, and the operation under very favorable conditions for the motor, insuring its even working, and the consequent lessening of noise and wear and tear of running the motor at excessive speeds, there- 55 by adding materially to the life and durability of the car and the pleasure of riding. Also with my mechanism it is possible to entirely disengage the driving pinions and permit the car to coast. 60

The objects of my invention are: First to provide in conjunction with the usual change-speed gear box an improved mechanism for two direct driving gears of different ratio. Second, to provide in a change 65 gear mechanism means whereby the rotation of the idling gears will be at low speed on their bearings with consequent avoiding of noise and lessening of friction. Third, to provide in such two direct driving gears an 70 improved arrangement of the driven gears in their relation to the differential gear housing. Fourth, to provide in such double direct driving gears an improved arrangement of gears in which the highest speed 75 gear is disposed in the outer position. Fifth, to provide, in conjunction with such two direct driving gears, an arrangement and disposition of the driven gears on the transverse axle whereby the clutch-operated 80 gear will be effectively supported by a bearing on the fixed gear. Sixth, to provide a gear construction and means especially well adapted to such additional high speed drive in that the high speed is accomplished by a 85 pinion meshing with the larger of a nested pair of driven gears. Seventh, to provide in a double driving gear structure an improved arrangement of parts for disconnecting the driving pinions and permitting 90 coasting.

Further objects, and objects relating to details and economies of construction and operation will definitely appear from the detailed description to follow.

I accomplish the objects of my invention 95

by the mechanism described in the following specification.

The invention is clearly defined and pointed out in the claims.

5 A structure which is a preferred embodiment of my invention is fully illustrated in the accompanying drawing, forming a part of this specification, in which:

10 Figure I is a right side elevation of the casing and connections of my improved change speed gearing, applied to a standard automobile construction. Fig. II is an enlarged detail plan view, partly in section and part of the casing removed, taken on a line corresponding to line 2—2 of Fig. I. Fig. III is an enlarged detail longitudinal sectional elevation view taken on the irregular line 3—3 of Fig. II, many of the parts being shown in full line. Fig. IV is a detail 15 transverse sectional elevation view taken on a line corresponding to line 4—4 of Figs. II and V, the shafts and certain other parts being shown in full lines. Fig. V is a detail sectional elevation view taken on a line corresponding to line 5—5 of Figs. II and IV, the differential gear parts being shown in full line. Fig. VI is an enlarged detail sectional view on line 6—6 of Fig. V, showing details of the adjustable joint between the 20 gears. Fig. VII is an enlarged detail sectional view on line 7—7 of Figs. I and II, showing details of the lever connection for controlling the clutches within my improved changed gear structure yielding indicator. Fig. VIII is an enlarged detail sectional view taken on a line corresponding to line 25 8—8 of Figs. II and III, showing details of the connection between the clutches and the clutch actuating means. Fig. IX is an enlarged detail sectional view on line 9—9 of Fig. VII, showing details of the yielding indicator. Fig. X is a detail sectional view of a modification of the driven gear clutch taken on a line corresponding to the line 40 4—4 of Fig. V. Fig. XI is a detail sectional view of a second modification of the driven gear clutch, also taken on a line corresponding to the line 4—4 of Fig. V. Fig. XII is a detail transverse view of the modified driven gear clutch, taken on a line 45 12—12 of Fig. II.

In the drawing, all of the sectional views are taken looking in the direction of the little arrows at the ends of the section lines, 50 and similar numerals of reference refer to similar parts throughout the several views.

Considering the numbered parts of the drawing, my improved gear changing mechanism is made use of in conjunction with 55 the ordinary and regular transmission of an automobile, which is indicated diagrammatically in Fig. I, the gears 1, 2 and 3 being shown by dotted lines within the gear-box 4.

A connection 5 for shifting the gears is 60 shown and the engine shaft appears at 6.

The propeller shaft 7 is incased in the usual casing 7', and is connected by a universal joint, not here illustrated, within the casing 8. As my invention does not have to do with these parts I have not deemed it necessary to 70 describe them in detail.

The propeller shaft 7 is within the casing 7' which casing is connected by suitable flanges 9 to the gear casing 10 which surrounds the differential gears, and my improved gear changer which is associated directly with the differential gears. The propeller shaft 7 is connected by slip joint 7^a or any suitable coupling to the short shaft 11, the meeting ends of the shaft being 75 square. Shaft 11 carries the driving pinion 12, preferably made integral with its inner end, although the same may be made separate and secured to the said shaft in any suitable way.

Journalized on the shaft 11 is a sleeve 13' carrying pinion 13 which is secured thereto by rivets 13^a through a suitable flange thereon. The outer end of this sleeve 13' is provided with clutch jaws 14. These are disposed to coact with a jaw clutch 15 which is carried on a square collar 15' that is suitably keyed or otherwise secured on the shaft 1. This clutch is controlled by clutch collar 16 which is controlled by the forked arm 17 which is connected to the rock shaft 48, clearly seen in Fig. VII. It will thus be seen that when the clutch 15 is thrown in the sleeve 13' and the pinion 13 will be connected to be driven by the shaft 11 so that when the clutch thus engages the shaft drives both of the pinions 12 and 13. The shaft 11 is preferably supported in ball bearings 35, 36, 37, for the forward end, which are adapted and formed to receive the thrust. A ball bearing 38, 39 at the rear end is carried by suitable cross-bar or yoke 40, or any suitable support. A collar 41 is on the rear end of the shaft 11, as clearly appears in Fig. III, and locks the ball bearing members to the shaft, and the outer ring is permitted to float in the yoke or support 40. The forward bearing is especially designed to receive the thrust.

The differential gear is provided with 115 two driven gears 24 and 29, which are engaged and driven by the pinions 12 and 13 respectively, see Figs. II, III and IV.

The differential itself is of the usual construction and drives the divided axle 18, 19. 120 The differential comprises gears 20, 21 and the intermediate gears 22, 22 carried within the differential housing 23 which is provided with a sleeve 25 which embraces the inner ends of the divided axle or shaft 18, 19. The sleeve of the differential is supported in suitable ball bearings 26, 26, which are retained in position by collars 27, 28 and are suitably embraced by the gear casing outside. The driven gear 24 is made 125 130

integral or secured directly to the housing of the differential, it being integral with the housing in this instance.

The driven gear 29 is nested into the gear 24 as clearly seen in Fig. IV, and is provided with a suitable bushing 30 which constitutes a journal bearing and embraces a journal on the sleeve 25. The face of the gear 29 is provided with clutch jaws 31 that 5 coöperate with the jaw clutch 32, see particularly Figs. II and IV. The jaw clutch 32 is disposed on a guard part of the sleeve 25 and is controlled by the collar 33, which has suitable pins extending into slots in the 10 levers 34, 34, which are fulcrumed within the case and extend outwardly and are coupled by the fork 49 to the rock shaft arm 17' which is carried by the vertical rock shaft 48, already referred to in this behalf. It will 15 thus be seen that whenever the clutch 15 is thrown in the clutch 32 will be thrown out and vice versa. When clutch 15 is thrown out then pinion 12 will drive the gear 29 because the same will be suitably clutched 20 by the clutch 32 and the differential will be driven by this means. When the clutch 15 is thrown in then the clutch 32 will be thrown out and the pinion 13 will drive the gear 24 which will drive the differential and 25 rear axle at a different rate.

The gear 29 is nested into a recess in the face of the gear 24. The gear 29 is provided with an annular bearing flange 45 which is secured thereto by suitable rivets 35 46, as clearly appears in Fig. IV. A co-operating annular bearing flange is detachably and adjustably secured within the recess on the said driven gear 24. This adjustable attachment is accomplished by a 40 double set of screws 43, 44. The screws 43, see the upper part of Fig. IV, are clamping screws and tend to draw the bearing 42 to place. The screws 44 are adjusting screws and enable the effective adjustment of the 45 bearing ring 42 so that it can be adjusted to nicely engage the bearing flange 45 and thus nicely support and guide the gears 49. By this means it is possible to provide a very broad bearing for the gear 29 and support the same as effectively as though it was 50 secured directly to the housing of the differential.

On the vertical rock shaft 48 I secure a spring finger 50 which coöperates with the 55 notched member 52, which is secured by bolts 53 to the horizontal flange of the casting, see Figs. I and VII. A series of notches 54 are provided on this member for the V shaped projection 51 of the said 60 spring 50 so that the clutch actuating mechanism is retained by a yielding stop in either of its engaged positions and at a middle or neutral position when neither clutch is engaged. When neither clutch is engaged 65 the driven axle is free to revolve with-

out carrying with it the driving or propeller shaft, and an automobile under such conditions coasts very freely, the engine and axle being thereby disconnected. It is clear from this that various yielding stops 70 might be provided. I have shown a simple form of such stops.

An inspection of Figs. II, III and IV will show that this structure is very compact and that it is readily retained within the 75 outer gear casing of the usual dimensions. It will also be observed that the gear ratio of the outer gear 24 and its pinion 13 is higher than that of the inner gear 24 and its pinion 12. When it is remembered that 80 this outer gear is for use under the most favorable road conditions it will be readily understood that it is of advantage to locate it in the position indicated so that the driving for the heavier work may be done by 85 the integral pinion 12 within the circumference of the said outer gear. The variations in speed sought are readily possible by this means and it is possible to thus nest the gears effectively together which it would not 90 be possible to accomplish in compact space by the reversed arrangement with the high speed gear at the interior. The outer gear is of higher ratio than the inner. For convenience in claiming, I shall denominate the 95 gears a high speed and a low speed gear. It will, therefore, be seen that the particular arrangement that I here point out secures a very compact and effective structure, making it possible to secure the two variations 100 of speed without substantially adding to the dimensions or weight of the usual differential gear and connections. It will also be observed that by this arrangement, whichever gear or pinion is idle will be 105 running at a relatively low rate of speed on its bearings, and because the whole of the structure is immersed in oil, or very thoroughly lubricated, no noise whatever is occasioned by this means, and owing to the 110 slow relative speed of the pinion, or of the gear as the case may be, there is no appreciable wear upon the idle parts when idle. This is of great advantage when it is understood that these parts receive the heaviest 115 wear of any of the gears of an automobile because they do all the work all the time.

The clutches, particularly the clutch for clutching the driving gear, is capable of wide modification. In Fig. X I show a 120 modification in which one member of the clutch, that is the member carried by the differential sleeve, is like an external spur gear, and the other member is a corresponding internal gear. The central portion of 125 the clutch driven gear 56 is a corresponding internal gear in other respects precisely like the gear 29, except the internal gear teeth are provided at the center. The clutch member 55 is disposed upon the squared portion 130

of the differential sleeve and is controlled by a clutch collar 33 precisely identical with that appearing in Fig. IV. In this gear it will be seen that the clutch driven gear has no bearing whatsoever on the sleeve of the differential. In Fig. XI I show a further modification of the clutch in which the central portion of the driven gear 60 is shown with a long hub 60' which is journaled upon the differential sleeve 25'. On this long hub is disposed a clutch member 58 which is controlled by the clutch collar 33 and is provided with pins 59 parallel with the axis thereof, which reciprocates through aperture 61 in the web portion of the driven gear 60 and are disposed and arranged to extend into holes 62 in the differential gear housing 22, and thus couple the clutch driven gear to the differential housing. The gear 60 is like gear 29 except the hub and clutch part. These are possible modifications of the clutch device, which I have in contemplation for use under different circumstances.

I desire to state that my gear changing mechanism may be greatly varied in its details without departing from my invention. I have shown the same in its approved form provided with ball bearings, and with the form of clutches and slip joint and other parts which I have found to be very effective in practice. I desire to state, however, that these details can be varied to a great extent without departing from my invention. I have shown a self contained clutch mechanism entirely within the case of the structure, with the exception of the projecting ends of the rock shaft and the connection thereto. These parts might be made use of under certain conditions without any casing, or the connections might be outside of the casing.

I have not shown a lever, or any means connected to operate the clutch. Levers and other means to throw clutches are common and I have not deemed it worth while to illustrate the same.

I have shown the form preferred by me, and which I desire to claim specifically, and I also desire to claim the invention broadly as pointed out in the appended claims.

Having thus described my invention, what I claim as new and desire to secure by Letters Patent is:

1. In a change speed gearing for automobiles, the combination of the axle, differential gearing with its housing and sleeve, a driven beveled gear secured to the differential gear housing, a second driven bevel gear nesting with the first beveled gear and journaled on the sleeve of the housing, a clutch for connecting said differential housing to said second driven gear, a propeller shaft with a pinion secured to the

end thereof, meshing with the inner driven gear, a sleeve journaled on the propeller shaft with a pinion meshing with the outer driven gear, a clutch for engaging the said sleeve and coupling said pinion to the said propeller shaft, a suitable casing for all of the said gearing, a rock shaft with arm for operating the clutch for the said pinion, an arm on the said rock shaft with connections to operate the clutch on the sleeve of the differential housing, connected and timed so that when the one clutch is engaged the other will be disengaged, and yielding stop means to retain the clutch in engaged or neutral position, co-operating substantially as described for the purpose specified. 80

2. In a change speed gearing for automobiles, the combination of the axle, differential gearing with its housing and sleeve, a driven beveled gear secured to the differential gear housing, a second driven bevel gear nesting with the first beveled gear and journaled on the sleeve of the housing, a clutch for connecting said differential housing to said second driven gear, a propeller shaft with a pinion secured to the end thereof, meshing with the inner driven gear, a sleeve journaled on the propeller shaft with a pinion meshing with the outer driven gear, a clutch for engaging the said sleeve and coupling said pinion to the said propeller shaft, a suitable casing for all of the said gearing, a rock shaft with arm for operating the clutch for the said pinion, and an arm on the said rock shaft with connections to operate the clutch on the sleeve of the differential housing, connected and timed so that when the one clutch is engaged the other will be disengaged, co-operating substantially as described for the purpose specified. 95

3. In a change speed gearing for automobiles, the combination of the axle, differential gearing with its housing and sleeve, a driven beveled gear secured to the differential gear housing, a second driven bevel gear nesting with the first beveled gear, a clutch for connecting said differential housing to said second driven gear, a propeller shaft with a pinion secured to the end thereof, meshing with the inner driven gear, a sleeve journaled on the propeller shaft with a pinion meshing with the outer driven gear, a clutch for coupling said pinion to the said propeller shaft, a suitable casing for all of the said gearing, a rock shaft with arm for operating the clutch for the said pinion, and an arm on the said rock shaft with connections to operate the clutch on the sleeve of the differential housing, connected and timed so that when the one clutch is engaged the other will be disengaged, co-operating substantially as described for the purpose specified. 110

4. In a change speed gearing for a motor vehicle, a driving shaft disposed longitudinally of the vehicle, a driven shaft disposed transversely thereto constituting the driven axle for said vehicle, a clutch-operated driving bevel gear concentric with the driving shaft, and a driving bevel gear fixed on the driving shaft, a bevel gear having a bearing surface on its face and fixed on the driven shaft and meshing with the clutch-operated driving gear, a clutch-operated bevel gear having a bearing surface on its back corresponding to the bearing surface on the fixed gear and concentric with the driven shaft, and clutches for said clutch-driven gears. 65
5. In a change-speed gearing for a motor vehicle, a driving shaft disposed longitudinally of the vehicle, a driven shaft disposed transversely thereto constituting the driven axle for said vehicle, a clutch-operated driving bevel gear concentric with the driving shaft, and a driving bevel gear fixed on the driving shaft, a bevel gear having a bearing surface on its face and fixed on the driven shaft and meshing with the clutch-operated driving gear, a clutch-operated bevel gear having a bearing surface on its back corresponding to the bearing surface on the fixed gear and concentric with the driven shaft, and clutches for said clutch-driven gears. 70
- 20 6. In a change-speed gearing for a motor vehicle, a driving shaft disposed longitudinally of the vehicle, a driven shaft disposed transversely thereto constituting the driven axle for said vehicle, a clutch-operated driving bevel gear concentric with the driving shaft, and a driving bevel gear fixed on the driving shaft, a bevel gear having a bearing surface on its face and fixed on the driven shaft and meshing with the clutch-operated driving gear, a clutch-operated bevel gear having a bearing surface on its back corresponding to the bearing surface on the fixed gear and concentric with the driven shaft meshing with the gear fixed on the driving shaft, an end thrust bearing for said clutch-operated driving gear, and clutches for said clutch driven gears. 75
- 25 7. In a change-speed gearing for a motor vehicle, a driving shaft disposed longitudinally of the vehicle, a driven shaft disposed transversely thereto, a clutch-operated driving bevel gear concentric with the driving shaft, and a driving bevel gear fixed on the driving shaft, a bevel gear fixed on the driven shaft and meshing with the clutch-operated driving gear, a clutch-operated bevel gear concentric with the driven shaft meshing with the gear fixed on the driving shaft, clutches for said clutch-driven gears, connections between the said clutches proportioned to actuate the same alternately, whereby both clutches cannot be engaged at the same time, and a connection for actuating the said clutches. 80
- 30 8. In a change-speed gearing for automobiles, the combination with the rear axle, differential gearing with its housing and sleeve, a driven beveled gear secured to the differential gear housing, a second beveled gear nesting with the first beveled gear and revoluble independently thereof, a clutch member carried by the differential gear structure for engaging the second driven gear, a propeller shaft with a pinion secured to the end thereof meshing with the inner driven gear, a second pinion supported by journal bearing on the propeller shaft, 85
- 35 9. In a change-speed gearing for automobiles, the combination of the axle, differential gearing and a suitable housing, an outer driven beveled gear secured to said housing and an inner driven beveled gear nested with the outer beveled gear, either one or the other of which is adapted to be connected to drive the differential gearing structure to operate the said axle, a propeller shaft, an inner pinion thereon adapted to mesh with the inner driven beveled gear, and an outer pinion concentric therewith adapted to mesh with the outer beveled gear, the outer gear and pinion being of higher ratio than the inner gear and pinion, 90 and means for coupling either the outer beveled gear and pinion, or the inner beveled gear and pinion to said propeller shaft to drive the said axle, coöperating for the purpose specified. 95
- 40 10. In a change-speed gearing for automobiles, the combination of the axle, differential gearing and a suitable housing, an outer driven beveled gear secured to said housing and an inner driven beveled gear nested with the outer beveled gear, either one or the other of which is adapted to be connected to drive the differential gearing structure to operate the said axle, a propeller shaft, a bearing for the inner end thereof, an inner pinion thereon adapted to mesh with the inner driven beveled gear, and an outer pinion concentric therewith adapted to mesh with the outer beveled gear, the outer gear and pinion being of higher ratio than the inner gear and pinion, 100 and means for coupling either the outer beveled gear and pinion, or the inner beveled gear and pinion to said propeller shaft to drive the said axle, coöperating for the purpose specified. 105
- 45 11. In a change-speed gearing for automobiles, the combination of the axle, an outer driven beveled gear and an inner driven bevel- 110
- 50
- 55
- 60

- eled gear nested with the outer beveled gear, either one or the other of which is adapted to be connected to drive the differential gearing structure to operate the said axle, 5 a propeller shaft, an inner pinion thereon adapted to mesh with the inner driven beveled gear, and an outer pinion concentric therewith adapted to mesh with the outer beveled gear, the outer gear and pinion being of higher ratio than the inner gear and pinion, and means for coupling either the outer beveled gear and pinion, or the inner beveled gear and pinion to said propeller shaft to drive the said axle, coöperating for the purpose specified. 10
12. In a change-speed gearing for automobiles, the combination of the axle, an outer driven beveled gear and an inner driven beveled gear nested with the outer beveled gear, either one or the other of which is adapted to be connected to drive the differential gearing structure to operate the said axle, a propeller shaft, a bearing for the inner end thereof, an inner pinion thereon adapted to 15 mesh with the inner driven beveled gear, and an outer pinion concentric therewith adapted to mesh with the outer beveled gear, the outer gear and pinion being of higher ratio than the inner gear and pinion, and means for coupling either the outer beveled gear and pinion, or the inner beveled gear and pinion to said propeller shaft to drive the said axle, coöperating for the purpose specified. 20
13. In a change-speed gearing for automobiles, the combination of the axle, differential gearing in a suitable housing, an outer driven beveled gear secured to said housing and an inner driven beveled gear, either one or the other of which is adapted to be connected to drive the differential gearing structure to operate the said axle, a propeller shaft, an inner pinion thereon adapted to mesh with the inner driven beveled gear, and an outer pinion thereon adapted to mesh 25 with the outer beveled gear, the outer gear and pinion being of higher ratio than the inner gear and pinion, and means for coupling either the outer beveled gear and pinion, or the inner beveled gear and pinion to said propeller shaft to drive the said axle, coöperating for the purpose specified. 30
14. In a change-speed gearing for automobiles, the combination of the axle, differential gearing in a suitable housing, an outer driven beveled gear secured to said housing and an inner driven beveled gear, either one or the other of which is adapted to be connected to drive the differential gearing structure to operate the said axle, a propeller shaft, a bearing for the inner end thereof, an inner pinion thereon adapted to mesh 35 with the inner driven beveled gear, and an outer pinion thereon adapted to mesh with the outer beveled gear, the outer gear and pinion being of higher ratio than the inner gear and pinion, and means for coupling either the outer beveled gear and pinion, or the inner beveled gear and pinion to said propeller shaft to drive the said axle, coöperating for the purpose specified. 40
15. In a change-speed gearing for automobiles, the combination of the differential gearing and its casing, with a driven beveled gear secured thereto, a second driven beveled gear nesting with the first, shouldered bearing rings, with both radial and thrust bearing surfaces, secured to the meeting faces of said gears, and means for adjusting the same whereby the one gear will support the other during its revolution, as specified. 45
16. In a change-speed gearing for automobiles, the combination of the differential gearing and its casing, with a driven beveled gear secured thereto, a second driven beveled gear nesting with the first, shouldered bearing rings, with both radial and thrust bearing surfaces, secured to the meeting faces of said gears whereby the one gear will support the other during its revolution, as specified. 50
17. In a change-speed gearing for automobiles, the combination of the differential gearing and its casing, with a driven beveled gear secured thereto, a second driven beveled gear nesting with the first, shouldered bearing rings secured to the meeting faces of said gears, and means for adjusting the same, comprising alternating clamping and setting screws through one of the said gears whereby the one gear will support the other during its revolution, as specified. 55
18. In a change-speed gearing for automobiles, the combination of the differential gearing and its casing, with a driven beveled gear secured thereto, a second driven beveled gear nesting with the first, and shouldered bearing rings secured to the meeting faces of said gears, as specified. 60
19. In a change-speed gearing, the combination of a driving shaft, a driven shaft disposed transversely thereto, driving beveled gears on said driving shaft, corresponding driven beveled gears on the driven shaft, clutch mechanisms for either set of gears, and a yielding stop means to hold the clutches in mesh or at neutral position. 65
20. In a change-speed gearing, the combination of a driving shaft, a driven shaft disposed transversely thereto, driving beveled gears on said driving shaft, corresponding driven beveled gears on the driven shaft, clutch mechanisms for either set of gears, and a yielding stop to hold the clutch at neutral position. 70
21. In a change-speed gearing for a motor vehicle, a driving shaft disposed longitudinally of the vehicle, a driven shaft disposed transversely thereto, a clutch-operated driving bevel gear concentric with the driving 75

shaft, and a driving bevel gear fixed on the driving shaft, a bevel gear fixed on the driven shaft and meshing with the clutch-operated driving gear, a clutch-operated bevel gear 5 concentric with the driven shaft meshing with the gear fixed on the driving shaft, clutches for said clutch-driven gears, actuating means for engaging said clutches alternately and independently, whereby both 10 clutches cannot be engaged at the same time,

and a connection for actuating the said clutches.

In witness whereof, I have hereunto set my hand and seal in the presence of two witnesses.
